BED ADJUSTING MECHANISM FOR STAMPING PRESSES

Original Filed Dec. 24, 1925

Attorney

UNITED STATES PATENT OFFICE

BROR J. LINDGREN, OF BUFFALO, NEW YORK, ASSIGNOR TO NIAGARA MACHINE & TOOL WORKS, OF BUFFALO, NEW YORK, A CORPORATION OF NEW YORK

BED-ADJUSTING MECHANISM FOR STAMPING PRESSES

Original application filed December 24, 1925, Serial No. 77,447. Divided and this application filed August 8, 1927. Serial No. 211,400.

This invention relates to a bed adjusting mechanism for sheet metal working presses such as sheet metal stamping presses and has for its object the provision of a mechanism for this purpose which permits of easily and conveniently adjusting the bed either while the press is at rest or in operation and which holds the bed reliably in position after adjustment.

10 This application is a division of the application filed December 24, 1925, Serial No. 77,447.

In the accompanying drawings:—

15 Fig. 1 is a fragmentary side elevation of a sheet metal working press equipped with my improved bed adjusting mechanism,

Fig. 2 is a front elevation of the same, and

20 Fig. 3 is a vertical longitudinal section on an enlarged scale, taken on line 3—3, Fig. 1.

25 The press shown in the drawings is primarily intended for notching and blanking operations on sheet metal in conjunction with an automatic mechanism arranged at a fixed level and operating to feed the metal to the notching or blanking press. It is to be understood however that this bed adjusting mechanism can also be used with a roll feed mechanism which operates at a fixed level and therefore requires adjustment of the die to 30 meet this level whenever the latter is resharpened by grinding off the top of the same. The grinding operation lowers the top of the die, hence the necessity for raising the same to the feed line which latter cannot be 35 changed.

In the following description, similar characters of reference indicate corresponding parts throughout the several views of the drawings.

40 This invention is applicable to sheet metal working presses particularly stamping and punching presses which may be of various forms as to their detailed construction and the particular press which is shown in the drawings is, therefore, to be taken as typical of one capable of use in connection with this invention. As there shown, the press comprises a main frame 10 which is mounted upon a base frame 11 and provided with a lower bed or table 12 which is adapted to support the

die or lower forming member, whereby the article is adapted to be shaped or punched, and an upper vertical guideway 13 in which a slide 14 moves vertically and is adapted to carry a punch or upper forming member adapted to cooperate with the lower forming member or die in the production of articles to be stamped or punched. This upper slide 14 is reciprocated vertically in its guideway by a horizontal shaft journaled transversely in a bearing on the upper part of the main frame and provided with a crank or wrist, which is connected with the slide 14 by means of a pitman or connecting rod so that a vertical reciprocating motion is imparted to the punch or upper die member during the rotary movement of the crank shaft in the usual and well-known manner in this type of stamping or punching presses.

55 In the present instance the blank or sheet to be cut or stamped is adjustably mounted by intermediate means on the bed or table 12 for the purpose of accurately fitting the die to the punch when setting up the press and also for taking up wear. The preferred form of these adjusting means is as follows:—

60 Movable vertically on the lower bed or table 12 is a lower slide having an upper head 19 adapted to carry the die and a lower shank 20 depending from the head and guided in vertical ways 21 arranged on opposite sides of an opening 22 in the bed 12. At its lower end this shank 20 is engaged by a vertically swinging lifting lever 23 which is pivoted at its rear end on the main frame by means of a transverse horizontal pin 24. The front end of the lifting lever 23 is provided with a longitudinal notch or slot 25 which receives the lower flat sided portion 26 of an upright lifting rod 27, said flat sided portion 26 engaging with the sides of the notch 25 so as to prevent this rod from turning in the lever 23, but still permitting an oscillating movement of the rod and lever relatively to each other in a vertical plane lengthwise of the machine. At its lower end the lifting rod is provided with a head 28 which bears against the lower convex or rounded side 29 of the lifting lever and its upper end passes through a vertical opening 30 formed in the front part of the

bed 12. This upper end of the lifting rod 27 is externally screw-threaded and receives an adjusting screw nut 31 which rests on top of the adjacent part of the bed 12 and is provided on the lower part of its periphery with a worm rim or wheel 32. Meshing with the front part of this worm wheel is a worm 33 which is secured to a horizontal transverse shaft 34 journaled in suitable central bearings 35, 35 and a side bearing 36, the bearings 35, 35 being formed on a bracket 37 which is detachably secured to the front side of the bed 12 and the bearing 36 being arranged on a hanger 38 which is detachably secured to the front side of the bed 12, adjacent to one corner thereof. The worm 33 is confined between the bearings 35, 35 so as to be held against longitudinal movement and rotation of this worm is effected by means of a handle or wheel 39 secured to the outer end of the shaft 34, as shown in Figures 1 and 2.

Upon turning the worm 33 by means of handle 39, the worm wheel 32 and the screw nut 31 formed thereon are turned about the lifting rod 27, whereby the latter is raised or lowered, depending upon which way the shaft 34 is turned. Upon raising and lowering the rod 27, the die mounted on the lower slide 19, 20, is adjusted accordingly through the medium of the lifting lever 23. The weight of these parts operates to keep the screw nut 31 and worm wheel 32 in engagement with the upper side of the front part of the bed 12, so that no separate means are required for keeping the parts in a normal position.

By means of this mechanism, the lower slide may be raised or lowered for the purpose of accurately adjusting the lower forming member or die to the fixed level of the feed 40 when setting up the press, and also when it becomes necessary to compensate for wear; and after these parts are adjusted they are reliably held in place without requiring any separate fastening for this purpose. Moreover, this means of adjusting the lower cutting member or die permits of effecting this adjustment while the press is in operation, thereby facilitating setting up the press and reducing the cost of production accordingly.

I claim as my invention:

1. A sheet metal working press having a bed, and means for adjustably mounting a lower die or tool relative to the bed comprising a lower slide adapted to carry said die and guided by the bed, and means for adjusting said die vertically relative to said bed comprising a lifting lever supporting said lower slide, a lifting rod connected at its lower end with said lifting lever, and a screw nut engaging with the upper end of said rod and resting on said bed.

2. A sheet metal working press having a bed, and means for adjustably mounting a lower die or tool relative to the bed comprising a lower slide adapted to carry said die

and guided by the bed, and means for adjusting said die vertically relative to said bed comprising a lifting lever supporting said lower slide, a lifting rod connected at its lower end with said lifting lever, a screw nut engaging with the upper end of said rod and resting on said bed, a worm wheel arranged on said screw nut, a worm meshing with said worm wheel and held against lengthwise movement, and a shaft carrying said worm and journaled in bearings on the bed and provided with a handle.

3. A sheet metal working press having a frame, a bed arranged on the frame, and means for adjustably mounting a lower die or tool relative to the bed comprising a lower slide adapted to carry said die and provided with an upper head and a shank depending from said head, said bed being provided with an opening which receives said shank and the opposite sides of said opening being provided with guideways in which the shank is guided, a vertically swinging lifting lever engaging the central part of its upper side with the lower end of the shank and having its rear end pivotally connected with the frame and its front end provided with a longitudinal slot, an upright lifting rod having a threaded upper end, a flat sided lower part engaging with the slot in said lever and a head at its lower end engaging with the lower side of the lifting lever, said bed being provided with an opening which receives the upper end of said rod, a screw nut engaging the threaded end of said rod and resting on the bed and having a worm wheel, a worm meshing with said worm wheel, a shaft carrying said worm, and bearings which are arranged on said bed on opposite sides of said worm and in which said shaft is journaled.

In testimony whereof I hereby affix my signature.

BROR J. LINDGREN.
